UNITED STATES PATENT OFFICE.

ROBERT L. ELLERY, OF TOLEDO, OHIO.

MECHANICAL MOVEMENT.

Application filed April 7, 1924. Serial No. 704,727.

To all whom it may concern:

Be it known that I, ROBERT L. ELLERY, a citizen of the United States, and a resident of Toledo, in the county of Lucas and State of Ohio, have invented a new and useful Mechanical Movement, which invention is fully set forth in the following specification.

This invention relates to mechanical movements, and particularly to such a movement adapted for use as a window raising and lowering mechanism.

The object of the invention is the provision of a simple, novel and efficient mechanism for translating a continuous rotary movement into an intermittent linear movement, and is adapted, when used as a window raising or lowering mechanism, to impart a rapid, positive raising or lowering movement to the window closure member, and, when at rest, to positively lock the window member against raising or lowering movements.

The invention is fully described in the following specification, and while in its broader aspect it is capable of embodiments in numerous forms, a preferred embodiment thereof is illustrated in the accompanying drawings, in which,

Figure 1 is an elevation of a mechanism embodying the invention partly broken away and associated with the door of a closed vehicle, the door being fragmentarily shown. Fig. 2 is a vertical fragmentary section of the door and associated window closure member with the mechanism embodying the invention in operative relation thereto. Fig. 3 is an enlarged section on the line 3—3 in Fig. 1. Fig. 4 is an enlarged section on the line 4—4 in Fig. 1. Fig. 5 is a fragmentary elevation of a portion of the mechanism illustrating the pawl actuating means. Fig. 6 is an enlarged cross-section on the line 6—6 in Fig. 1, and Fig. 7 is an enlarged fragmentary perspective view of a portion of the mechanism.

Referring to the drawings, 1 designates the door of a closed automobile, which door is provided in its upper portion with a window opening 2 adapted to be closed by a glass or window member 3 and forming in its lower portion a chamber 4 into which the window member may be lowered and in which the control means for the window member is disposed. The door is provided

with the customary cross bar 5 in the upper portion of the chamber 4 at the outer side.

The mechanism embodying the invention includes an elongated frame member 6 of shallow channel form which is secured in upright position to the cross member 5 of the door within the chamber 4. This frame has its side edges provided with flanges 7, which extend away from the cross member 5 and which render the frame 6 of shallow channel form. The frame 6 is provided with a centrally disposed, longitudinal slot 8 and has a longitudinally extending portion 9 on its back or inner side which forms a guide-way 10 lengthwise of the slot 8 and which extends at either side of the slot, as best shown in Figs. 6 and 7. The bottom plate portion of the frame 6 has a wing 11 extending from a side edge thereof in a common plane therewith and over the door member 5, the flange 7 being omitted from the edge portion of the frame from which the wing projects.

A slide block 12 is mounted in the guide 10 for longitudinal reciprocatory movements therein and a stub shaft 13 projects from this plate outwardly through the slot 8 and beyond the frame 6. A grooved roller 14 on which the lower edge of the window member 3 is intended to rest is carried by the projecting end of the shaft 13, and a pawl 15 is also carried by this shaft next to the bottom plate of the frame 6. This pawl, in the present instance, is suspended from the shaft 13 for free rocking movements relative thereto and is provided at its lower end with oppositely projecting rack bar engaging teeth, thus making the pawl of substantially T form.

A pawl actuating plate 16 is mounted within the channel of the frame 6 against the bottom thereof and has a longitudinally extending slot 17 in register with the frame slot 8 and substantially co-extensive in length therewith but slightly wider than the same. The slot 17 is intended to receive the pawl 15 and in width is equal to the cross-sectional dimension of the toothed end portion of the pawl so that any transverse movement of the plate 16 within the frame 6 will impart a rocking movement in one direction or the other to the pawl, as is apparent by reference to Figs. 5 and 7. The plate 16 is mounted on guide-pins 18 projecting from the bottom of the frame 6 and

is provided with transversely extending slots 19 through which the pins extend, thus causing the plate to be supported against longitudinal movement relative to the frame 5 and permitting it to have limited transverse movement relative thereto. The plate 16 has a wing 20 projecting over the wing 11 of the frame 6 in sliding contact therewith and provided with a cam receiving opening 21.

A rack bar 22 is mounted over the pawl actuating plate 16 at each side of its slot 17 and has its rack teeth facing the teeth of the other rack bar. One rack bar is disposed 15 in position for its teeth to be engaged by the adjacent tooth of the pawl 15 when swung in one direction, and the other rack bar is disposed in position for its teeth to be engaged by the other tooth of the pawl 20 when the pawl is swung in the other direction, the pawl being released from one rack bar when in engagement with the other. Each rack bar is mounted for limited reciprocal movements longitudinally of the 25 frame 6, and for such purpose has a series of longitudinally extending slots 23 which receive the pins 18 that project through the registering slots 19 of the pawl actuating plate 16, the slots 19 and 23 being disposed 30 in right-angular relation to each other. A pin 25 projects from the frame 6 between the rack bars 22 near the lower ends thereof and has its arms of equal length and pivoted to the respective rack bars, thus providing a connection between the rack bars 35 which causes them to have corresponding opposed reciprocal movements when either one is reciprocated.

The rack bar 22 at the side of the frame 40 6, from which the wing 11 projects, has a wing 26 projecting from its outer edge over the wing 20 of the pawl actuating plate 16 and is provided with a cam receiving opening 27.

45 An operating shaft 30 is journaled in suitable bearings provided in the cross member 5 and frame wing 11 and projects at one end without the inner side of the door 1 to receive an operating crank 31, and has its opposite end disposed substantially centrally within the opening 21 and 27 of the wings 20 and 26. A cam 32 is mounted on the shaft 30 within said openings, and, in the present instance, is provided with three 50 uniform cam faces of 120° each, which faces are of like radius and are struck from different centers offset from the shaft center. The cam 32 is of sufficient thickness to extend within the openings of both wings 20 and 26, and so co-acts with the walls of the opening 21 of the pawl actuating plate 16 that a turning of the cam will impart a predetermined, transverse, reciprocal movement first in one direction and then the 60 other to such plate relative to the frame, the

plate being guided during such movements by the pins 18 in the plate slots 19. Nothing novel is claimed in itself for this manner of actuating the plate 16, as such cam means is old in the art. The cam 32 co-acts at top 70 and bottom with the upper and lower edge walls of the rack bar opening 27 in a manner to impart successive upward and downward reciprocal movements to the rack bar at successive points in a turning of the 75 cam, as is well understood in the art. In order to provide the wing 26 with broadened bearing surfaces for the cam, the metal of the wing is outwardly flanged at the upper and lower edges of the opening 27, as shown 80 at 33. It is apparent that a complete revolution of the three shaft cam shown will impart three upward movements and three downward movements to the rack bar 22, to which it is immediately connected, and that 85 it will likewise impart three movements in one direction and three in the other to the pawl actuating plate 16. It is also apparent that inasmuch as one of the rack bars is moving upward while the other is moving 90 downward, the two rack bars will combine to have six movements, three for one and three for the other, in the same direction during a complete revolution of the cam.

In an operation of the device a turning 95 of the cam will operate to transversely shift the pawl actuating plate 16 to throw the pawl into engagement with one or the other of the rack bars 22 and immediately thereafter the rack bars will be moved lengthwise of the frame 6 to impart a predetermined raising or lowering movement, as the case may be, to the member supported by the roller 14. When this movement of the 100 rack bar has been completed the cam will again act on the plate 16 to move it in the opposite direction from its previous movement so as to release the pawl from engagement with one rack bar and move it into engagement with the other. The cam then 105 immediately acts on the rack bar with which it has engagement to move it in the opposite direction from that in which it was previously moved and this imparts a movement to the rack bar with which the pawl is engaged in the same direction that the pawl was moved by the other rack bar in the preceding advancing operation. This step by step raising or lowering movement of the pawl and the actuating member 3 to 110 115 which it is connected is continued during a continued turning of the cam until the member has been raised or lowered the desired extent. When the cam is at rest the pawl 120 125 is always in engagement with one or the other of the rack bars so as to positively lock the mechanism against actuating movements except through an operating of the cam.

It is apparent that inasmuch as three ad- 130

vancing movements are imparted to the actuating member 3 at each complete rotation of the cam, quite a rapid raising or lowering movement is imparted to the member and that such movement is positive in its action.

I wish it understood that my invention is not limited to any specific construction, arrangement or form of the parts as it is capable of numerous modifications and changes without departing from the spirit of the claims.

Having thus described my invention, what I claim as new and desire to secure by Letters Patent is:

15 1. In combination, a member to be actuated, a pair of rack bars, a connection between the rack bars causing them to have opposed reciprocatory movements in unison, a pawl having connection with said member, means operable to move the pawl to alternately engage the rack bars, and means having a rotatable control part operable to impart pawl shifting movements to said pawl actuating means and also operable to 20 impart longitudinal reciprocatory movements to one of said rack bars.

2. In combination, a sliding member, a pair of transversely spaced rack bars, connection between the rack bars for causing them to move longitudinally in opposite directions when one is moved, a pawl connected to the sliding member and operable to alternately engage the teeth of the rack bars, a rotatable cam operable during a continuous rotation thereof to impart reciprocatory movements to one of said rack bars, and means actuated by a rotation of the cam intermediate the rack bar movements to move the pawl into engagement with first one and then the other of the rack bars.

3. In combination, a pawl mounted for linear movements in one plane and for shifting movements transversely thereof, means connected to and actuated by the linear movements of said pawl, a pair of rack bars spaced transversely of the pawl and reciprocally movable in planes longitudinal to the linear movement of the pawl, connection between the rack bars for imparting opposed reciprocatory movements from one to the other when one is moved, and means having a rotatable actuating part for shifting the pawl into engagement with first one and then the other of the rack bars and after each shifting movement of the pawl to impart longitudinal movement in first one and then the other direction to one of said rack bars.

4. In combination, a part mounted for reciprocal movements, a pawl means connected to and movable with said part, a pair of rack bars reciprocally movable in planes substantially parallel to the plane of movement of said part and connected to have opposed movements in unison when either

is moved, and means having a rotatable actuating part and operable to move said pawl means into engagement with the teeth of first one and then the other of said rack bars and to impart reciprocatory movements 70 to one of said rack bars and through it to the other during each period of engagement of the pawl with a rack bar.

5. In combination, a part mounted for reciprocal movements, a pawl means connected to and movable with said part, a pair of rack bars reciprocally movable in planes substantially parallel to the plane of movement of said part and connected to have opposed movements in unison when either is moved, and means having a rotatable actuating member operable at different predetermined intervals in a single rotation of the member to impart a plurality of shifting movements to the pawl means to engage first 80 one and then the other of the rack bars and operable to impart reciprocatory movement to one of the rack bars and through it in an opposite direction to the other rack bar during each period of engagement of the pawl 85 with a rack bar.

6. In combination, a part mounted for reciprocatory movements, a pawl means connected to and movable with said part and being shiftable transversely of the direction of movement of the part, a pair of rack bars movable longitudinally of the direction of movement of the part and adapted to have simultaneous uniform movements in opposite directions, means shiftable transversely of the movement of the rack bars to shift the pawl means into engagement with the teeth of first one and then the other of the rack bars, and means having a rotatable actuating cam operable to move the pawl shifting means in first one direction and then the other and after each shifting of the pawl to actuate the rack bars to move the pawl and connected part 100 a predetermined distance.

7. In combination, a frame member guided for reciprocatory movements by said frame, pawl means carried by said member, and mechanism for actuating said pawl means to impart step by step movements in one direction or the other thereto, said mechanism comprising a pair of rack bars, and means operable to alternately engage the pawl means with first one and then the other of said rack bars and to impart opposed reciprocatory movements to the bars when the pawl means is in engagement with either, whereby first one and then the other of the bars imparts movement in the same direction to the pawl means and member.

8. In combination, a frame, a member guided for reciprocatory movements by said frame, pawl means carried by said member, a pair of rack bars reciprocally movable longitudinally of the direction of movement

- of said member and connected to have opposed reciprocatory movements in unison when either is moved, means guided for movements transversely of the movements 5 of the rack bars and adapted, when moved in one direction, to cause the pawl means to engage one rack bar and when moved in the other direction to cause the pawl means to engage the other rack bar, and 10 manually controlled means operable to impart predetermined alternating reciprocatory movements to the means for shifting said pawl means and to one of said rack bars.
- 15 9. In combination, a slidable window member, a stationary frame, a pair of rack bars guided by the frame for reciprocatory movements longitudinally of the movements of the window member and operable to have 20 opposed reciprocatory movements when either is moved, means engaging the window member and guided by the frame for reciprocatory movements lengthwise of the window member movement, whereby the 25 window member and means move together, said means having a pawl shiftable to alternately engage said rack bars, and mechanism manually operable to reciprocate one of the rack bars and to shift the pawl of said 30 means into engagement with first one and then the other rack bar to impart a step by step movement in one direction or the other to the window member engaging means.
10. In combination, a slidable member, a 35 guide frame, an actuating means for the member guided for reciprocatory longitudinal movements by the frame and having a pawl, rack bar means having two rack

bars carried by the frame for opposed reciprocatory movements in unison lengthwise 40 of the movement of said actuating means and adapted to be alternately engaged by the pawl whereby the rack bars alternately impart step by step movements in either direction through the pawl to the actuating 45 means, means operable to shift the pawl into engagement with first one and then the other of the rack bars, and control means operable to impart movement to the pawl shifting means and to impart reciprocatory 50 movements to the rack bars to the member actuating means in one direction or the other.

11. In combination, a slidable member, a stationary frame, an actuating means for 55 said member guided by the frame for movements lengthwise of the movement of said member and having a pawl, a pair of rack bars guided by the frame for parallel reciprocatory movements longitudinally of the 60 movements of said means, means connecting the rack bars to cause them to reciprocate in opposite directions when either is moved, a pawl actuating member guided by the frame for reciprocatory movements transverse to the movements of the rack bars and adapted to shift the pawl into engagement 65 with first one and then the other of the rack bars, and rotatable control means having cam engagement with one of said rack bars 70 and with said pawl actuating member to impart predetermined respective, reciprocatory movements thereto when operated.

In testimony whereof I have hereunto signed my name to this specification.

ROBERT L. ELLERY.
